DESIGN FOR A PORTABLE ELECTRIC FAN

Charles E. Jones, Chicago, Ill., assignor to Charles E. Jones and Associates, Inc., Chicago, Ill., a corporation of Illinois

Application December 9, 1948, Serial No. 150,058

Term of patent 14 years

(Cl. D26—7)

To all whom it may concern:

Be it known that I, Charles E. Jones, a citizen of the United States, residing at Chicago, in the county of Cook and State of Illinois, have invented a new, original, and ornamental Design for a Portable Electric Fan, of which the following is a specification, reference being had to the accompanying drawing, forming a part thereof.

In the drawing:

Fig. 1 is a view, in perspective, of a portable electric fan showing my new design;

Fig. 2 is a front view, in elevation, of the electric fan; and

Fig. 3 is a side view, in elevation, of the electric fan.

The characteristic features of my design reside in the portions shown by means of full lines in the drawing.

I claim:

The ornamental design for a portable electric fan, substantially as shown and described.

CHARLES E. JONES.
